UNITED STATES PATENT OFFICE.

JOSEPH J. BENEDICK, OF OAKLAND, CALIFORNIA.

STEAM-SHOVEL.

No. 876,517.

Specification of Letters Patent.

Patented Jan. 14, 1908.

Application filed August 2, 1907. Serial No. 386,691.

To all whom it may concern:

Be it known that I, JOSEPH J. BENEDICK, a citizen of the United States, and a resident of Oakland, in the county of Alameda, State 5 of California, have invented certain new and useful Improvements in Steam-Shovels, of which I declare the following to be such a full and clear specification as to enable those skilled in the art to construct and use the 10 same.

This invention relates to machines which are used for the purpose of shoveling large amounts of earth by power, and the object of the invention is to make a shovel that will 15 be strong enough to stand the hard service of such machines.

A further object of the invention is to make a shovel that will have the capability of acting toward the car which supports the 20 frame as well as in a direction upwards, as is the common style of such shovels.

The common type of shovel is used with a cable which lifts the shovel from the ground with the full power of the engine, but it is 25 often necessary to make the shovel take out ground that has been left in the forward movement of the shovel, and the shovel must then be dropped down on the dirt pile, or the bucket turned over in order that the pile of 30 dirt that has been left may be broken up.

Another object of this invention is to make a shovel which will be capable of digging the ground toward the car as well as away from it, and since the arrangement of the boom 35 and mast, with its cables is such as to make it possible to work the shovel toward the car the shovel can take out the leavings of ground that with many machines must be taken out by hand, or by moving the ma- 40 chine bodily.

In the drawings, in which like numerals of reference are applied to like parts throughout, Figure 1 is a side elevation of a part of a car with the shovel in place, and Fig. 2 is a 45 front view of the car with the boom and lifting arm taken off.

Only a part of the car is shown, the car being broken away in the middle. The car is supported by the wheels 1 on the frame of 50 which is carried the bolster 2 which supports the bed 3 of the car. Near the front end of the car there are two uprights 23 which are secured together at their tops by means of the girder 5, said posts and girder being 55 braced in their places by the braces 4 which incline toward the top of the posts 23 from a

point in the rear. Near the center of the frame thus formed is placed the double posts 6 which are secured together and which are free to turn in a plane at right angles with the posts 23, side posts 6 having a large pulley 7 at the bottom and about which runs the cable 8 which is used for the purpose of turning the shovel to any desired position, the cable leading to any suitable power drum. 60

The double posts 6 carry the shovel 18 by means of the boom 11 and handle 17, the boom 11 being pivoted in two plates near the bottom of the posts 6 and being free to move in a vertical plane. The shovel handle 17 is 70 pivoted on the end of the boom 11 and it also is free to move in a vertical plane. The movements of the boom 11, handle 17 and shovel are controlled by means of the cable 20, the lifting arm 12 and the cable 21. 75

The cable 20 is secured at one end to a point near the middle of the under side of the boom 11, it then passes around a pulley 27 carried by the under side of the shovel handle 17, and back to a point near the bottom of 80 the boom 11, where there is secured in the pivoted posts 6 a small pulley 25, shown in dotted lines in Fig. 1, then it passes down around another pulley 26 which is carried by the frame of the car, and then to the drum 10. 85 The upper cable 21 is secured to the posts 6 at one end from which point it passes to the pulley 28 carried by the top of the shovel handle 17, then back to the pulley 24 and down around a pulley at the side of the pulley 26 and up to the drum 9. Now it will be observed that these ropes pass so near to the center of motion of the posts 6 that the cables are not injured in any way when the posts are turned to one side for the turning is 90 made in vertical parts of the ropes. 95

The ropes above described are for the purpose of handling the shovel on the end of the boom, but it is also necessary to handle the boom, and this is done by means of the arm 12 which is provided with rack teeth which are engaged by the pinion 14 which is operated by means of the gear 13 in mesh with the gear 15 driven by means of the engine 16 which latter is carried by the pivoted posts 6, 100 and swings around with them. Now it will be observed that with this construction that it is possible to push the boom 11 down as hard as it may be pulled up, a thing which would not be possible were the boom lifted by 105 means of cables, since then only the weight of the shovel and boom could be used to 110

break hard ridges of dirt down on the back stroke.

The shovel 18 is provided with the usual door 22, but in addition it is also provided 5 with the teeth 19 which are extended beyond the shovel proper both in the front and in the rear of the bucket, thus making it possible to break the dirt as easily in the direction toward the car as away from it, and the 10 shovel can thus be used as a pick, since absolute control of it is given by means of the arm 12 and the cables 20, 21.

It will also be observed that there is a further advantage in the construction shown 15 on account of the location of the pulleys below the car frame since it makes the pull on the drums 9 and 10 down and thus there is no tendency for them to be shifted should they be insecurely fastened to the car body.

20 It is thought that the operation of the machine will be clear from the above description. The boom 11 can be pushed down or raised with the full power of the engine 16, and the shovel may be positively handled 25 in the same way by reason of the fact that it has cables attached to it above and below the point at which it is pivoted to the boom 11.

What I claim as new and desire to secure 30 by Letters Patent of the United States, modifications within the scope of the appended 35 claims being expressly reserved.

1. In a steam shovel, the combination of a platform, a vertical frame carried thereby, a mast pivoted at its top in said frame and at 35 the bottom in the platform, a boom pivoted at its lower end to the mast and near the bottom thereof, a rigid arm pivoted to the boom, means on the mast to forcibly raise or depress the raising arm, and a shovel carried by the boom.

2. In a steam shovel, the combination of a platform, a frame carried thereby, a mast pivoted at its top in said frame and at its bottom on said platform, a boom carried by the 45 mast and adapted to have a movement in a vertical plane, a raising arm pivoted at its end to the boom, means to forcibly raise and depress the raising arm, a shovel carried by the boom, and means to forcibly raise and 50 depress the shovel.

3. In a steam shovel, the combination of a platform, a frame carried thereby, a mast pivoted at its top in the frame and at its bottom on the platform, a boom carried by the 55 mast and having a movement in a vertical plane, a raising arm pivoted at one end to the boom and extending through the mast, means carried by the mast to forcibly raise and depress the raising arm and boom, a shovel carried by the boom, and means to forcibly raise and 60 depress the shovel.

4. In a steam shovel, the combination of a platform, a frame carried thereby, a mast pivoted in the frame and on the platform, a boom carried by the mast and adapted to be 65 moved in a vertical plane with respect to the mast, a raising arm carried at one end by the boom and passing through the mast, means to forcibly raise and depress said arm and the boom, a shovel carried by the boom at its 70 end, means to raise and means to depress the shovel.

5. In a steam shovel, the combination of a platform, a frame carried thereby, a mast pivoted in said frame and on the platform, a boom pivoted at its lower end to the mast and near the lower end thereof, a raising arm pivoted at one end to the boom and passing through the mast, an engine carried by the mast, a gear connected to the engine and 80 adapted to raise or depress the arm, a shovel carried by the boom, means to raise the shovel and means to pull the shovel toward the platform.

6. In a steam shovel, the combination of a platform, a frame carried thereby, a mast pivoted in the frame and on the platform, a boom carried by the mast, means to forcibly raise and depress the boom, a shovel carried by the boom, said shovel having digging teeth 90 at the front and rear, means to raise the shovel, and means to draw the shovel toward the platform.

7. In a steam shovel, the combination of a shovel body and teeth carried by the body 95 extending in the front and in the rear of the shovel body.

8. In a steam shovel, the combination of a power shovel body, teeth carried by the body and extending in the front and in the rear of the shovel body, and means to move the shovel to the front and the rear.

9. In a steam shovel, the combination of a platform, a frame carried by the platform, a mast pivoted in the frame and on the platform, means to rotate the mast in a horizontal plane, a boom carried by the mast and pivoted to the same near the bottom thereof, a raising arm carried by the boom and passing through the mast, means carried by the mast 105 to raise and depress the arm, a shovel carried by the boom, means to raise the shovel and means to draw the shovel toward the platform.

In testimony whereof I have hereunto set 115 my hand in the presence of two witnesses this 13th day of July, A. D. 1907, at San Francisco, State of California.

JOSEPH J. BENEDICK.
